UNITED STATES PATENT OFFICE.

OWEN W. DAVIS, OF BANGOR, AND GEORGE D. COLBY, OF KATAHDIN IRON WORKS, MAINE.

ORE ROASTING AND CALCINING FURNACE

SPECIFICATION forming part of Letters Patent No. 247,542, dated September 27, 1881.

Application filed August 10, 1880. (No model.)

To all whom it may concern:

Be it known that we, OWEN W. DAVIS, of Bangor, in the county of Penobscot, and GEORGE D. COLBY, of Katahdin Iron Works, 5 in the county of Piscataquis, and State of Maine, have invented certain new and useful Improvements in Ore Roasting or Calcining Furnaces; and we do hereby declare that the following is a full, clear, and exact description 10 of the invention, that will enable others skilled in the art to which it appertains to make and use the same, reference being had to the accompanying drawing, forming a part of this specification, in which the figure shows a vertical 15 section.

Our invention consists of an improved furnace for roasting ore, and is more especially designed for treating those ores of iron which contain large proportions of sulphur, although 20 its usefulness is not limited to such.

With the ordinary furnace the fumes of the sulphur reaching the top of the chimney and coming in contact with the cold air are condensed and a considerable portion falls back 25 upon the ore, without doubt owing to the fact that the ascending draft is stronger at the sides of the chimney, allowing the central part to be comparatively without draft to oppose the descent of the products of condensation. Our 30 object is the remedy of this defect, and will be understood by reference to the accompanying drawing.

A shows an ordinary furnace, circular in form, having the usual fuel-arches, *b*, ore-drawing 35 openings *c*, and feed-openings *d*, above which latter extends the chimney *e*. Within this furnace we construct a hollow pier, *f*, circular in cross-section like the furnace itself, built of fire-brick to a height of some fifteen feet, (more 40 or less,) so that its top may be above the intense heat. This pier is pierced with openings *g* from the level of the fuel-arches upward. Upon its top we erect a chimney or funnel, *h*, for which purpose wrought-iron is a good material, extending it to the top of the furnace. A at or near its point of junction with its 45 surrounding chimney *e*, at which place it is braced and held in position by appropriate device sufficiently to sustain any blow or shock from the 50 descending ore as it is fed to the furnace.

This funnel, with its supporting pier supplied with openings connecting with the roasting ore, carries off the sulphur, forming a central draft, which, in connection with the chimney *e*, effectually prevents any return of the concentrated fumes, and converting the ore-roasting space *i* into an annular chamber, with a perfect draft to its summit. At *j* is an opening for conveniently cleaning the pier and funnel. 55

This form of furnace may also be used to advantage in calcining lime and for similar purposes where a central draft will be an advantage. 60

If preferred, the fire-brick pier may be extended to the top of the furnace, thus dispensing with the funnel *h*; but this would not in any manner affect the operation of our invention, being simply an equivalent for said funnel. 65

We do not claim the devices shown in the 70 patents of J. Renton, February 28, 1854, No. 10,574, and T. J. Chubb, November 19, 1872, No. 133,202. Neither of these shows an annular ore-roasting chamber, by which device we avoid the central core of cold air and little 75 draft common to ordinary furnaces; nor does the central pier or conductor in either case communicate with the chimney or stack of the furnace, and through it to the air, so as to increase the central ascending draft. In the 80 Renton patent it simply serves as a conductor to carry the distilled gases to a reservoir, serving the same function as the worm of a still, while that shown in Chubb's patent is simply to introduce hot air into his gas-chamber. 85

We do not claim a suspended flue, as shown in the patent of W. S. Sampson, dated April 7, 1874. This does not form an annular ore-roasting space, which is an important feature of our invention; nor would such a device operate to take the products of combustion from that part of the ore-body subjected to intense heat, as the flue would burn off up to a point where the ore was comparatively cool, thus diminishing the amount of internal draft. The 95 fire-brick pier supporting the funnel and perforated, as described, is an essential part of our invention, enabling the heated products to be taken from the hottest part of the roasting ore-body, and thereby adding to the efficiency 100

of the internal draft in removing the sulphur, &c. Nor do we claim a portable chimney for brick-kilns, as shown in Hamilton's Patent No. 101,124.

5 By the use of the term "annular" we do not intend to limit ourselves to the precise form of furnace used, as the desired result might be produced by other shapes, the interior pier and funnel approximating in form to the surrounding furnace and producing a variation in the form of the ore-roasting space without changing the principle of our invention.

What we claim as our invention is—

An improved ore roasting or calcining furnace embodying an ordinary furnace, A, a central fire-brick pier, f, with openings j therein for cleaning the same, and openings g, communicating with the surrounding ore-space i,

and a funnel, h, supported by said pier, extending to the top of the furnace, and forming, with 20 said pier, a supplemental central chimney or flue resting upon the floor or base of said furnace and extending to its top, and communicating both with said ore-space and with the open air through the furnace-chimney e, substantially as and for the purposes described.

In testimony that we claim the foregoing we have hereunto set our hands.

OWEN W. DAVIS.
